UNITED STATES PATENT OFFICE.

WILLIAM E. MOREY, OF CHICAGO, ILLINOIS, ASSIGNOR TO NATIONAL DUMP CAR COMPANY, A CORPORATION OF MAINE.

DOOR-ACTUATING MECHANISM.

1,186,118.

Specification of Letters Patent.

Patented June 6, 1916.

Application filed June 25, 1914. Serial No. 847,235.

To all whom it may concern:

Be it known that I, WILLIAM E. MOREY, a citizen of the United States, residing at Chicago, in the county of Cook and State 5 of Illinois, have invented certain new and useful Improvements in Door-Actuating Mechanism, of which the following is a specification.

This invention relates to improvements in 10 door actuating mechanism, and has for its object to provide a new and improved mechanism of that character in combination with cars having dump doors.

The principal object of my invention is to 15 provide a new and improved means for operating the dump doors and means for locking and supporting such doors when in closed position.

Still another object is to provide means in 20 conjunction with the above, for locking the supporting members in supporting position.

Still another object consists in the provision of a new and improved structure to affect the above and other objects.

25 My invention is set forth and described in the following specification and accompanying drawings, in which:

Figure 1 is a side elevation of a portion of a car showing my invention applied thereto; 30 Fig. 2 is a vertical transverse section of the same; Fig. 3 is a detail side elevation of the operating mechanism; Fig. 4 is a detail plan view, partially in section, with the supporting and locking shaft; Fig. 5 is a 35 vertical transverse section showing a detail of my invention; Fig. 6 is a view similar to Fig. 5 on another plane.

Like numerals refer to like elements throughout the drawings, in which 10 indicates generally a car having the side walls 11 supported by and attached to the stakes 12. Extending downwardly from the lower portion of the walls 11 to the floor of the car, and inclined with respect thereto, are 45 the deflecting walls 12. The car is further provided with the doors 13 at the bottom thereof, these doors being hinged at 13^a for opening or closing thereof. Each of the doors 13 is provided with the attached Z- 50 bars 13^b on the bottom thereof adjacent the side edges. An angle bar 13^c is attached to the front and bottom of each of these doors 13 and to a flange of this angle 13^c is attached the end link of a chain or other flexible member 14 and at their other ends these

chains 14 are attached to an operating shaft 15 which is journaled in the upwardly extending plates 16 which have base flanges 16^a riveted or otherwise attached to the under side of the deflecting walls 12. At its ends 60 the shaft 15 is provided with a ratchet or star wheel 18 attached thereto. This wheel 18 is provided with the hub portion 18^a upon which is rotatably mounted a collar 19 formed integrally with an outwardly extending socket 19^a in which may be fitted an operating lever or the like. A washer or flange 20 may be provided adjacent the hub 18^a to prevent accidental displacement of the collar 19, the said flange 20 being preferably held in place by a cotter pin 20^a, or the like. Mounted on the shaft 15 adjacent the ratchet or star wheel 18, is a second ratchet or star wheel 21 which coacts with a pawl 22 or detent 22 pivotally mounted upon the 70 pin 22^a carried by the adjacent brackets 16. This pawl 22 is so arranged as to permit its engagement with the star wheel 21 to prevent unwinding of the shaft 15 while permitting winding thereof, as will be apparent to those skilled in the art. A dog or pawl 19^b is pivotally mounted on a pin 19^c carried by socket 19^a and is so arranged as to permit its movement into engagement with wheel 18 in such wise that when a handle inserted in socket 19^a is oscillated forward and back, the said pawl 19^b will slip over the ratchet 18 when moving in one direction and will engage the same on its reverse movement to rotate the shaft 15, the 80 pawl 22 preventing a return or reverse movement of the shaft 15 during such winding thereof. Through this mechanism I am enabled to rotate the shaft 15 in the proper direction to wind the chain 14 thereon to 90 affect a closing or partial closing movement of the doors 13.

Partition webs or cross plates 25 extend transversely of the car 10 below the floor thereof and are located between and at the 100 ends of the doors 13, as shown in Figs. 1 and 2 for example. These plates 25 are provided near their outer ends with slots 25^a extending from adjacent such outer ends upwardly and inwardly of the said plates or webs 25, as is clearly shown in Fig. 2, for example. These slots are provided with their inner ends approximately horizontal or slightly downwardly turned as indicated at numeral 25^b, see 110

Figs. 2 and 6, for a purpose to be hereinafter described. Extending through these slots and mounted for movement therein are the shafts 30 substantially parallel with and located near the shafts 15. Chains or flexible members 31 extend approximately at right angles to the axis of the shaft 30 and are looped one or more times around said shaft, the ends being secured to eye bolts 32, 33 carried by the car structure. If necessary in some instances I may attach the chains at a proper point to the shaft to prevent relative slipping. At their ends the shafts 30 are provided with the collars 34 secured thereto and each provided with a star or ratchet wheel 35. Mounted upon this collar or hub 34 is a ring or collar 36 similar to number 19, and similarly carrying a socket 36^a in which may be inserted a lever 20 or operating handle. A pawl 37 is pivotally attached to a pin 37^a carried by socket 36^a, see Fig. 3, and is intended to coact with star or ratchet wheel 35 in a manner similar to that explained and described in connection with ratchet 18, the purpose being to enable rotation of shaft 30 to be affected by oscillation of socket 36^a. Rotation in the proper direction of shaft 30 will result through the medium of chains 31 in bodily movement or rolling of the said shaft from one extreme of the slots 25^a to the other thereof, as is clearly illustrated in Fig. 2. On the left side the shaft 30 is shown at one limit of its travel, while on the right hand side it is shown at the other limit of travel.

The purpose of this structure is to effect the absolute closing and supporting of the doors 13, the operation being as follows:—When the shaft 15 has been rotated to almost 40 close the doors 13, the same may be held in partially closed position by means of a pawl 22 and ratchet 21, described above, while the shaft 30 is bodily moved from the position shown at the left hand side of Fig. 2 to that 45 shown in Fig. 6, during which movement the said shaft will contact with the lower surface of Z-bars 13^b, and through the inclination of the slots 25^a the shaft 30 will force the doors 13 to closed position as illustrated 50 at the right hand side of Fig. 2. Owing to the provision of the horizontal or slightly down-turned portion 25^b of slots 25^a, the shafts 30 will be held against accidental displacement such as would permit the sudden 55 opening of the doors 13 and throw the entire weight thereof on chains 14. Shafts 30 are even more firmly held in position, supporting and locking the doors 13 when the car is loaded and the weight of such load is 60 resting on said shafts 30. This construction is further advantageous in that it transmits and distributes the load in the car to and throughout the car under-frame, as will be apparent. To further guard against accidental movement of the shaft 30 from sup-

porting position, I provide the additional locking means shown in Fig. 5 and comprising the stop arm 40 pivotally mounted at 40° adjacent one extremity to a portion of the adjacent web or plate 25. This stop arm is provided with a concaved end 40^b adapted to closely fit and contact with a portion of collar 34 and by its location it is apparent that when the stop arm 40 is in the position shown in Fig. 5, it will directly 75 resist return movement of the shaft 30 from supporting position. To retain this stop arm 40 in its locking position, shown in Fig. 5, I provide the locking cam 41 pivotally mounted at 41^a. This cam is so arranged 80 that it may be swung into the position shown in Fig. 5 directly beneath and contacting with the under-side of stop arm 40 thereby forcing it tightly against the shaft 30 and retaining it in such position. This cam 85 41 is provided with the engageable portion 41^b which may be utilized in moving it from or to locking position. A strip 42 extends between the pivotal points 40^a, 41^a and serves to hold stop arm 40 and cam 41 against lateral movement.

It is believed that the description above is sufficient to render the construction and operation of the device clear to those skilled in the art. I would state further, however, 95 that in releasing or opening the doors to permit discharge of a load, the following operation is performed: The pawl 22 is thrown to unlocking position, thereby permitting release of the door closing shaft 15. 100 The locking cam 41 is then thrown out of locking position, permitting the drop arm 40 to drop or be forced to released position, whereupon the shaft will move or may be moved by means of socket 36^a and pawl 105 37 from beneath the doors permitting the same to drop and discharge said load.

While I have shown and described my device with more or less particularity, I do not wish to be restricted thereto beyond the 110 scope of the appended claims.

What I claim is:—

1. In combination with a car having a hinged door, a shaft operatively connected to said door and operable to partially close the same, and a member located in a plane lower than said shaft and bodily movable to move said door from partially closed position to a wholly closed position.
2. In combination with a car having a hinged door, a shaft located in a plane above that of the door when closed operatively connected to said door and operable to partially close the same, and a member operable to move said door from partially closed position to a wholly closed position, said member being arranged to support said door in closed position.
3. In combination with a car having a hinged door, a shaft located in a plane above 130

the door when closed and operatively connected to said door and operable to partially close the same, a member located in a lower plane than said shaft and operable to move 5 said door from partially closed position to a wholly closed position, said member being arranged to support said door in closed position, and means to lock said member in supporting position.

10 4. In combination with a car having a hinged door, means to move said door to closed position, a shaft, and means to rotate and move said shaft beneath said door, said means comprising a flexible member fixed 15 on either side of said shaft and carried around said shaft.

5. In combination with a car having a hinged door, means to move said door to closed position, a shaft, means to rotate and 20 move said shaft beneath said door, said means comprising a flexible member fixed on either side of said shaft and carried around said shaft, and a pawl and ratchet mechanism whereby said shaft may be rotated, 25 said flexible member causing said shaft to move bodily beneath said door when rotated.

6. In combination with a car having a hinged door, means to close said door, a shaft movable beneath said door to support the same in closed position, said shaft being mounted to move on an inclined path, and means to lock said shaft in supporting position, said means comprising a pivoted member 30 adapted to be swung to or from position locking said shaft in supporting position.

7. In combination with a car having a

hinged door, means to close said door, a shaft movable beneath said door to support the same in closed position, said shaft being 40 mounted to move on an inclined path, means to lock said shaft in supporting position, said means comprising a pivoted member adapted to be swung to or from position locking said shaft in supporting position, 45 and means to support said member in position locking said shaft.

8. In combination with a car having a hinged door, means to close said door, and a shaft movable beneath said door to support 50 the same in closed position, said shaft being mounted to move on an inclined path, and means to lock said shaft in supporting position, said means comprising a stop arm pivoted adjacent one extremity to move to or 55 from position locking said shaft.

9. In combination with a car having a hinged door, means to close said door, a shaft movable beneath said door to support the same in closed position, said shaft being 60 mounted to move on an inclined path, means to lock said shaft in supporting position, said means comprising a stop arm pivoted adjacent one extremity to move to or 65 from position locking said shaft, and a cam member pivoted to move to or from position locking said stop arm in engagement with said shaft.

In testimony whereof, I have subscribed my name.

WILLIAM E. MOREY.
